P. T. SHARPLES,
METHOD OF REFINING PETROLEUM,
APPLICATION FILED MAR. 12, 1920.

Patented May 23, 1922.

UNITED STATES PATENT OFFICE.

PHILIP T. SHARPLES, OF ST. DAVIDS, PENNSYLVANIA.

METHOD OF REFINING PETROLEUM.

1,416,890.

Specification of Letters Patent. Patented May 23, 1922.

Application filed March 12, 1920. Serial No. 365,135.

To all whom it may concern:

Be it known that I, PHILIP T. SHARPLES, a citizen of the United States, residing at St. Davids, in the county of Delaware and 5 State of Pennsylvania, have invented a certain new and useful Method of Refining Petroleum, of which the following is a specification.

This invention is a petroleum refining 10 method designed primarily to improve the product and increase the yield of lubricating oils, as also to reduce the time, simplify the installation for and reduce the cost of refining.

15 In the usual present commercial method, the crude oil (from which foreign matters such as water, dirt and "B. S." have been removed) is steam distilled by the application of fire and steam to the oil contained 20 in the still. The products distill off in the order of their boiling points, in sequence as gas, naphtha, burning oils, light lubricating distillate and heavy lubricating distillate, these being separately condensed and 25 collected and leaving a residue in the still known as cylinder stock. The light lubricating distillate thus obtained contains paraffin wax, which wax is removed therefrom by chilling and filter pressing. The heavy lubricating distillate, on the other hand, contains wax which cannot be removed by 30 filter pressing, for the wax is in such a condition that it rapidly clogs up the filter medium. Such heavy oils must therefore 35 be redistilled or "cracked." The wax is thus changed to the crystalline state and is removed by filter pressing. This redistillation of the heavy lubricating distillate is 40 objectionable because a large part of the oil is broken down into naphtha, burning oils, and coke, and the remainder is much lower in viscosity than in its former condition. This loss of oil and change in viscosity is 45 an unavoidable consequence of bringing the wax to a condition in which it can be removed by filter pressing.

The light lubricating distillate and the product, "cracked" distillate, obtained by redistilling the heavy lubricating distillate 50 are very much the same and are frequently combined and filter pressed together. In filter pressing the crystalline paraffin, wax remains in the filter press, the wax free oils passing therethrough. The wax free oils 55 must then be redistilled to produce the various viscosities which are required for lu-

brication. In this distillation, the spindle oils (the very light lubricating oils) are distilled off, distillation continuing until the residue has the required viscosity. This 60 residue is commonly referred to as "neutral" oil.

The residue in the still from the first distillation of crude is gravity settled to remove the wax by dilution with naphtha, 65 chilling, settling, drawing off the clear supernatant liquid and reducing, producing bright cylinder stock. The bright cylinder stock and the neutral oils are then blended to produce various market products of in- 70 termediate viscosities.

By the method of my invention, the lubricating residue in the still, after the removal of gas, naphtha and burning oils by distillation and before the distillation of the light 75 lubricating oils, is diluted with naphtha, chilled and passed through a centrifugal separator from which the wax free diluted lubricating residue is discharged on the one hand and the wax on the other. The bright 80 lubricating residue is then steam distilled by which there are obtained in succession the naphtha used in dilution, the spindle oil and the finished product of lubricating oil which remains as a residue in the still, the 85 distillation being continued until this residue has the viscosity and fire test required in the finished product.

This improved method not only eliminates 90 the cracking distillation of the heavy lubricating oils together with further recited operations of the former method, but it greatly increases the yield of finished lubricating oils, it avoids all of the several "overhead" distillations of the former method 95 and resulting deterioration of valuable lubricating products by the high temperatures necessary for driving the lubricating oils "overhead," and it further avoids the necessity in the former method of installing two 100 complete and separate outfits for the removal of the wax, namely, an outfit comprising a filter press for the separation of crystalline wax and another comprising the gravity settling means for the removal of 105 amorphous wax from cylinder stock.

The accompanying drawing is a comparative diagrammatic illustration of the characteristic operations of my improved method together with the old method, the 110 eliminated operations of the known method being indicated by broken lines.

As illustrated, in accordance with both the old and the new method, the crude oils (free of foreign matters) are heated in the still 1 from which gas, naphtha and burning oils are passed off through the condenser 1^a and the conduit 2 provided with branches 3, 4 and 5 to indicate the separate collection of these constituents.

In accordance with the method usually practiced heretofore, the distillation is continued so as to carry "overhead" the light lubricating distillate, which passes off through the conduits 2, 6 and 7 to a press 8; thereafter the heavy lubricating distillate, which passes off through the conduits 2 and 9 to a still 10, where cracking distillation is effected, and cylinder stock is carried off through the conduit 11 to the gravity settling tank 12. Naphtha passes off from the still 10 through the conduit 13 and the condenser 13^a, and thereafter light lubricating distillate, which flows through the conduits 13, condenser 13^a, 14 and 7 to the press 8, leaving a residue of coke as indicated by the conduit 15. The press 8 delivers wax free oil, which flows through the conduit 16 to the still 17, and paraffin, which is delivered through the conduits 16 and 18. The still 17 delivers in succession, through the conduit 20, spindle oil as indicated by the branch conduit 21 and neutral lubricating oil as indicated by the conduit 23. The lubricating oil flowing through the conduit 23 is blended with the gravity separated bright cylinder stock drawn off from the tank 12 through the conduit 24, the separated petrolatum in the tank being indicated by the conduit 25.

In accordance with the method of my invention, after the gas, naphtha and burning oils have been passed off from the still 1 through the conduit 2, the lubricating residue is drawn off from the still through the conduit 26, this residue being diluted 45 with naphtha and chilled to precipitate the amorphous wax. The chilled oil is passed from the conduit 26 through the centrifugal separator 28 which separates the wax from the bright lubricating residue. The wax is delivered from the separator, as indicated by the conduit 29, and the bright lubricating residue is discharged through a conduit 30 to the still 31, which delivers in succession, the naphtha used in dilution and 50 spindle oil through the conduit 32, and the finished residual lubricating product through the conduit 34.

As a definite illustration of the practice of my invention the following example is given:

Pennsylvania crude petroleum was distilled with fire and steam to remove the gas, naphtha and other light ingredients, until the distillate coming off showed a specific gravity corresponding to 84° Bé. This

residue which contained a large amount of wax in the so-called "amorphous" state was then diluted with 60% of straight cut naphtha of a specific gravity corresponding to 57° Bé, and the mixture was heated to about 70 100° F. to insure complete solution of the wax. The mixture was then cooled and chilled to a temperature of -10° F., care having been taken to chill the wax gradually. During the chilling the wax was 75 stirred slowly to keep the distribution and nature of the wax uniform, the desire being to prevent, as far as possible, the formation of very fine wax particles which might tend to be held in colloidal suspension and to secure uniformity of distribution of the wax in order to reduce the necessity for changing the adjustment of the centrifugal machine. After the stock was thus properly chilled, it was in this instance treated in a 80 centrifugal machine operated in accordance with my Patent 1,232,104, from which oil and wax were continuously and separately discharged. The oil and wax were then separately distilled to remove the naphtha, 85 and the oil which resulted was a heavy lubricating oil having the physical properties of a finished product.

Having described my invention, I claim:

1. The method of treating a petroleum residue obtained by distilling off gas, naphtha and burning oils from crude petroleum without cracking the residue substantially, which consists in chilling the residue obtained thereby with precipitation of the wax 95 therein; subjecting the chilled residue to centrifugal treatment adapted for separating wax from the residue, and separately discharging the separated wax and the wax freed residue continuously.

2. The method of treating residue obtained by distilling off the gas, naphtha and burning oils from crude petroleum without cracking the residue substantially, which consists in diluting the residue; chilling the 100 diluted residue with precipitation of wax therein; subjecting the chilled diluted residue to centrifugal treatment adapted to separate wax therefrom and separately discharging the wax and the wax freed product 110 continuously; distilling off the diluent, and distilling the wax freed residue.

3. The method of refining the lubricating residue obtained by distilling crude petroleum without cracking said residue substantially, which consists in chilling said residue with precipitation of wax therein; centrifugally separating precipitated wax from the chilled residue with flotation thereof on an immiscible carrier liquid, and steam distilling the separated bright lubricating residue.

4. The method of refining crude petroleum which consists in distilling off the more volatile constituents until a residue is obtained

which will have (after the removal of the wax therefrom) the physical properties required in a finished lubricating product, diluting said residue, chilling the diluted product with precipitation of wax therein, subjecting the chilled product to centrifugal treatment adapted to separate wax therefrom and separately discharging the wax freed product, and distilling off the diluent from said wax freed product with the production of the desired lubricating product.

5. The method of treating a petroleum product containing wax, which comprises in diluting and chilling the same with the

10 precipitation of the wax (without crystallization thereof), subjecting the chilled diluted product to centrifugal treatment

adapted to separate the wax therefrom, and separately discharging the separated wax and the wax freed product continuously. 20

6. The method of refining the residue of crude petroleum obtained by distilling off the lighter constituents without substantially cracking the residue, which consists in chilling said residue with precipitation of wax 25 therein; centrifugally separating wax from the chilled residue with flotation thereof on brine; and distilling the centrifugally separated bright lubricating residue to drive off the lighter from the residual heavier lubricating oils. 30

In testimony whereof I have hereunto set my name this 8th day of March, 1920.

P. T. SHARPLES.
